UNITED STATES PATENT OFFICE.

MARK SMITH, OF REDDISH, NEAR STOCKPORT, ENGLAND.

BRONZING AND LIKE MACHINE.

1,136,623.

Specification of Letters Patent.

Patented Apr. 20, 1915.

Application filed February 7, 1914. Serial No. 817,116.

To all whom it may concern:

Be it known that I, MARK SMITH, a subject of the King of Great Britain and Ireland, and a resident of Reddish, near Stockport, in the county of Chester, England, have invented new and useful Improvements in Bronzing and like Machines, of which the following is a specification.

This invention relates to flat bed bronzing or the like machines of the type in which a traveling belt passes around drums or pulleys and carries a card or sheet of paper or other material under or against various applying, polishing or equivalent devices, and which belt is provided on its outer surface with spring gripper plates which close by their own springiness to grip upon the outer surface of the belt the sheet or card and carry such sheet or card under the polishing devices, and are operated by means of cam devices disposed inside the belt.

This invention consists in a particular construction of spring gripper plate. Any number of such plates may be used in combination with each other to form a complete gripping device along the leading edge of a sheet or card. The improved gripper consists of a single strip of sheet steel or other metal longitudinally disposed on the belt and secured at its leading end to the under or inner side of the belt in such a manner as to normally exert a gripping pressure by its rear end on the outer surface of the belt. The steel strip is sufficiently bowed or bent to engage with a ramp and then to pass through a hole in the belt. The part which projects from the outer surface of the belt is bent and flattened to form the gripper plate and to close the holes in the belt, and may extend to any convenient distance on each side of the part which passes through the belt. Ramps or the like may be employed to open the gripper, or parts of the drums or pulleys around which the belt passes may themselves open the gripper as the latter passes around them.

The accompanying drawings illustrate a flat bed traveling belt bronzing machine provided with gripping devices constructed,

disposed and operated according to this invention.

Figure 1 is a general view in vertical section of the machine. Fig. 2 is an enlarged plan view of part of the traveling belt, showing one of a row of the improved grippers. Fig. 3 is a sectional side view of the parts shown in Fig. 2, and also illustrates one form of device for operating the gripper, the gripper being shown in its closed or gripping position. Fig. 4 is a view generally similar to Fig. 3 but shows the gripper in its open position.

Referring chiefly to Fig. 1, A is the casing of the machine; B, B, the bronze applying and polishing rollers; C a traveling belt moving continuously in one direction for carrying the cards or sheets of papers under the rollers B; D and D¹ the pulleys around which the belt passes placed respectively at the feed and delivery ends of the machine; E a table or flat support over which the belt passes beneath the polishing rollers; F, rollers between which the bronzed sheet may be dusted back and front; G a fan by which air and suspended bronze dust are drawn from the machine and an inward air draft or current into the machine from the work room is caused; and S a separator in which the bronze dust so withdrawn from the machine is separated from the air and can be returned to the machine for re-use. Except for the grippers on the belt the above described parts may be of any usual and convenient construction.

The grippers illustrated as constructed according to this invention consist of a number of thin steel spring strips or plates H laid in a row at suitable distances apart across the belt C, each plate or strip being parallel to the edge C¹ of the belt. The leading end of each plate or strip is secured to the under side of the belt by a rivet K. The strip curves or is bowed downward away from the belt, and then passes upward through a hole c in the belt. The rear or following end of the plate or strip is bent or formed as at H¹ (see Figs. 3 and 4) and it is this end which grips the sheet upon the belt.

The form of the plate and its attachment to the belt are such that its own springiness will maintain it, when it is free to do so, in the gripping position shown in Fig. 3. The 5 downwardly curved portion of each plate is the part which is engaged by an operating device to open the gripper. To freely permit the passage of these parts the pulleys D and D¹ are formed with circumferential 10 grooves properly placed and of sufficiently large dimensions. In these grooves, however, are placed the gripper operating devices L, those acting in conjunction with the roller D at the feed end of the machine being 15 additionally shown in Figs. 3 and 4.

When a gripper is traveling through the position shown in Fig. 4 its downwardly curved part runs up the curved front and upper edge of the operating device L and 20 lifts the part H¹ of the gripper off the belt. The gripper is then open and remains open until its curved portion reaches the rear of the ramp L, when the spring of the plate forces the plate end H¹ down on to the face 25 of the belt. The gripper is then closed. This is illustrated in Fig. 3.

When the grippers are in the position of Fig. 4 the front edge of a sheet or card is placed under their rear ends H¹, that part 30 of each plate which passes through the belt acting as a stop to the edge of the sheet. When the grippers reach the position of Fig. 3 the parts H¹ are pressed firmly down on to the surface of the belt and the sheet is firmly 35 gripped between them and the belt. The grippers and sheet then are carried by the belt beneath the bronzing rollers B. The table E if used, has longitudinal grooves or recesses to freely permit the passage of the 40 downwardly curved parts of the plates H.

When the grippers arrive at the delivery end of the machine they are again opened and closed by devices L of like construction and disposition to those already described as 45 being at the feed end of the machine. While the grippers are open at the delivery end the edge of the sheet may be seized by delivering devices of any suitable or known construction which pass between the various 50 plates H¹ disposed in a row across the belt and effect the delivery of the sheet. Or any other convenient delivery appliances may be used.

In the machine illustrated in Fig. 1 the grippers are shown as disposed across the belt in three rows. One row is indicated at 1, another at 2, and the third at 3. The row at 1 is shown with the component plates in their closed positions having just gripped a sheet 55 M to draw it under the rollers B. The row at 2 is shown with the springs or plates open to deliver up the sheet which they have just drawn under the rollers B. The row at 60 3

has its strips closed and idly passing to the feed end of the machine to take up another sheet.

The devices by which the sheets or cards may be fed correctly to the grippers may be any of those known and used in printing, bronzing and like machines. Or, if desired, the feeding may be effected by hand. The belt may be made of any of the materials usually employed for such belts, and the rear ends H¹ of the gripping plates may come down directly upon the substance of the belt, 75 or, at the points where such ends grip the sheets the surface of the belt may be provided with thin protective plates. The edges of the belt preferably pass along against the sides of the casing and may be 80 perforated as indicated at C² in Fig. 2, such perforations serving the double purpose of engaging with the teeth of wheels secured to the shaft of the pulley D¹ and of freely permitting the passage of air from the space 85 surrounding the belt into the chamber formed and inclosed by the belt. In this chamber is the port or opening N leading to the fan G. The chamber inclosed by the belt may have a tray on which bronze dust 90 may settle. This settled bronze dust may be brushed to the opening N.

What I claim is:—

1. In a traveling belt bronzing machine comprising a traveling belt, and means for 95 driving the same, spring grippers thereon composed of spring plates attached to the inner surface side of the belt and projecting through holes in the belt to the outer surface thereof where they are provided with 100 gripper ends which completely close the holes in the belt, and means situated within the loop of the belt adapted to coöperate with parts of the spring grippers to open and permit the closing of such grippers as 105 they move over such means, substantially as described.

2. On a traveling carrying belt for a bronzing machine, a spring gripper composed of a spring plate the leading end of 110 which is attached to the inner surface of the belt the outer end of which passes through a hole to the outer surface of the belt where it is formed with a gripping end which completely closes the holes in the belt, and 115 the intermediate portion of which projects away from the inner surface of the belt in a manner suitable for engagement with means for lifting the gripping end away from and permitting it to return to the outer surface 120 of the belt, substantially as described.

3. In a traveling belt bronzing machine comprising a traveling belt, and circumferentially grooved pulleys for the same, spring grippers composed of spring plates attached 125 by their leading ends to the inner surface of

the belt, such spring grippers being formed with rear parts which pass through the belt to the outer surface and are formed as gripping ends which completely close the hole in the belt and with intermediate parts which project from the inner surface of the belt, and means disposed within the circumferential grooves in the pulleys to operate the grippers by engagement with their project-

ing intermediate parts, substantially as hereinbefore described. 10

In witness whereof I have hereunto set my hand in the presence of two subscribing witnesses.

MARK SMITH.
